UNITED STATES PATENT OFFICE.

JAMES WEATHERS, OF INDIANAPOLIS, INDIANA, ASSIGNOR OF ONE-HALF
TO JOHN A. ROBBINS, OF SAME PLACE.

WHIP-SOCKET.

SPECIFICATION forming part of Letters Patent No. 291,856, dated January 8, 1884.

Application filed November 8, 1883. (No model.)

To all whom it may concern:

Be it known that I, JAMES WEATHERS, a citizen of the United States, residing at Indianapolis, in the county of Marion and State of Indiana, have invented certain new and useful Improvements in Whip-Sockets, of which the following is a specification, reference being had therein to the accompanying drawings.

10 This invention relates to certain improvements in whip-sockets for carriages and other vehicles; and it has for its objects to provide for locking the whip in the same, so that it cannot be lost or stolen, as more fully herein-after specified. These objects I attain by the means illustrated in the accompanying drawings, in which—

15 Figure 1 represents a view partly in elevation and partly in section, showing my invention; and Fig. 2, a detached view of a key for locking and unlocking the whip.

The letter A indicates a whip-socket of the ordinary or any approved construction, which is provided at one side with a tubular extension, B, preferably located near the bottom. 20 The wall of the socket, at the point from which the projection extends, is pierced, and is pro-

vided with a threaded gland, D, through which passes a screw-threaded shank, F, having a suitable head, H, which bears against the butt 30 or other portion of the whip to lock it in the socket. The said shank is squared or angular at its outer end, so as to receive a key, G, by means of which it may be screwed up against the whip to bind it to its seat. The squared 35 or angular end of the shank F sets within the tubular extension, so that it cannot be turned by any instrument except a proper key.

Having thus described my invention, what I claim, and desire to secure by Letters Patent, 40 is—

The combination, with a whip-socket, of a tubular extension having a threaded gland, and the threaded shank having a swiveled head and a squared or angular end to receive 45 a key, whereby it may be operated to lock and unlock the whip, substantially as specified.

In testimony whereof I affix my signature in presence of two witnesses.

JAMES WEATHERS.
